UNITED STATES PATENT OFFICE.

BRIDGET T. BING, OF NEW YORK, N. Y.

SANITARY TOILET-SEAT COVER.

Application filed October 11, 1927. Serial No. 225,427.

This invention relates to a sanitary seat cover for toilets and has for one of its objects the provision of a cover which is of inexpensive construction and which may be conveniently folded for dispensing at counters or by vending machines.

Another object of my invention is the provision of a sanitary seat cover for toilets which is adapted to be folded to adapt the same to seats of different sizes and which when folded provides a cover of triple thickness at the front portion of the seat.

Other objects will appear hereinafter, the novel features and combination being set forth in the appended claims.

In the drawings:

Fig. 1 is a developmental view of a cover embodying my invention.

Fig. 2 is a plan view of my invention in folded position.

Fig. 3 is a fragmentary sectional view taken on the line 3—3 of Fig. 2.

Fig. 4 is a plan view of a modified form of my invention.

Fig. 5 is a fragmentary top plan of a further development of my invention.

Fig. 6 is a sectional view taken on the line 6—6 of Fig. 5.

Referring particularly to the drawings the numeral 10 designates a sheet of paper comprising tissue paper or other suitable material having a substantially elliptical circumference. Hole 11 of substantially elliptical contour is provided in the central position of the sheet 10 and the inner edge portion of the sheet 10 is provided with spaced apart notches or slits 12. It should be understood that the sheet 10 may be employed in the shape illustrated in Fig. 1 and

that when it is so employed its dimensions are slightly greater than the dimensions of a toilet seat and the opening 11 is of dimensions slightly less than the opening or hole in a toilet seat. The above described arrangement permits that portion of the cover between the notches 12 to be disposed downwardly around the inner edge portions of the toilet seat upon which it is mounted without causing tearing of the material

50 of the cover. A tongue or extension 10^a is provided on the cover for facilitating removal thereof without requiring handling of the main portion.

It should also be understood that the cover 10 may be folded as illustrated in Figs. 2 and 3 and that when the cover is so

employed the sheet material comprising the cover is of larger dimensions than the seat of a toilet and the sheet is provided with perforations disposed in straight lines for indicating portions to be folded and rendering the portions easily foldable. As illustrated in the developmental view the sheet is provided with inner perforated lines 13 and 14 and the outer perforated lines 15 and 16. The perforated lines are symmetrically arranged and divide the sheet into an inner front section 17 and outer front sections 18 and 19.

During the folding operation the front inner section 17 is permitted to remain substantially flat while the sections 19 and 18 are folded inwardly and disposed in superimposed relation at the top of the section 17 with the portions of the material having the perforated lines 14 and 15 therein adjacent to each other. The adjacent portion of the ring member 10 is folded downwardly along lines 14 and 15 and disposed in superimposed relation on top of the sections 18 and 19, it being understood that the sections 18 and 19 are disposed between the inner front section 17 and the portions of the ring member 10 which are immediately adjacent to the sections 18 and 19. The above described construction provided a cover having a triple thickness of material at the front thereof as illustrated in Fig. 3. It should also be understood that any desired number of perforated lines 13, 14, 15 and 16 may be provided for rendering the cover member foldable to conform with seats of different sizes.

In the modified form of my invention illustrated in Fig. 4 the cover member 20 is of horseshoe shape and is adapted to be positioned on a toilet seat for covering the front portion thereof while the rear is left uncovered.

In the form of my invention illustrated in Figs. 5 and 6 the seat cover 10' is formed in the manner described above and is identical in construction with the seat cover 10 of Figs. 1, 2 and 3. The seat 10' has lines of perforation 13', 14', 15' and 16' formed therein dividing the cover into sections 17', 18', and 19' as above described. In this form of my invention, the sections 17', 18', and 19' and those sections of the material immediately adjacent to the sections 18' and 19' are provided registering slots which form tabs or flies 21, 22 and 23 integral at an end

with the sections 17', 18' and 19' respectively, and tabs 24 and 25 on the sections adjacent the sections 18' and 19'. These tabs are all adapted to be placed in registration 5 with each other when the device is folded as above described, and the tabs are adapted to be folded downwardly as illustrated in Figs. 5 and 6 for securing the section in folded position. It should be understood that the 10 seat cover illustrated in Figs. 5 and 6 and in Figs. 1, 2 and 3 may be sold on the market in the folded condition shown or they may be sold in unfolded condition so as to be folded by the user to the size required.

15 The cover which is used in this invention is preferably made of material which may be dissolved in water.

While I have described my invention with some degree of particularity I realize that 20 in practice various alterations therein may be made, I therefore reserve the right and privilege of changing the form of the details, or otherwise altering the arrangement of the correlated parts without departing 25 from the spirit or the scope of the appended claims.

Having thus fully shown and described an embodiment of my invention what is desired to be secured by Letters Patent of the 30 United States is:

1. A toilet seat cover of the class described comprising a substantially U-shaped section, an inner front section, and outer sections between the extremities of said inner section and the extremities of the U-shaped section, said sections being divided by perforated lines extending from the inner edge to the outer edge thereof and disposed in superimposed relation with said inner front section in the bottom portion of said U-shaped section on the top and said outer sections therebetween.

2. A toilet seat cover of the class described comprising a substantially U-shaped

section, an inner front section and a tab 45 formed integral with each of said section adapted to be disposed downwardly for retaining the front portion of said cover in folded position, outer sections between the extremities of said inner section and the extremities of the U-shaped section, said sections being divided by perforated lines extending from the inner edge to the outer edge thereof and disposed in superimposed relation with said inner front section in the 50 bottom portion of said U-shaped section on the top and said outer sections therebetween.

3. A cover of the class described comprising an integral elliptical ring comprising a front downwardly folded section disposed substantially parallel to the plane of the ring and two intermediate sections extending from the folded edges of the downwardly disposed section to the adjacent portions of the ring member, the downwardly disposed section extending across the front portion of the ring for covering a gap between the creased portions of the ring proper.

4. A cover of the class described comprising an integral elliptical ring comprising a front downwardly folded section disposed substantially parallel to the plane of the ring and two intermediate sections extending from the folded edges of the downwardly disposed section to the adjacent creased portion of the ring proper, the downwardly disposed section extending across the front portion of the ring for covering a gap between the creased portions of the ring proper, and flap formed by registering slots 70 cut in the ring proper, intermediate sections and the downwardly disposed section adapted to be folded downwardly in superimposed relation for holding the folded sections securely in place.

In testimony whereof I have affixed my signature.

BRIDGET T. BING.
